US0D1108250S

(12) **United States Design Patent** (10) **Patent No.:** **US D1,108,250 S**
(45) **Date of Patent:** **** Jan. 6, 2026**

(54) **WIRE CLAMP HOOK**

(71) Applicant: **Chupeng Zhan**, Huizhou (CN)

(72) Inventor: **Chupeng Zhan**, Huizhou (CN)

(**) Term: **15 Years**

(21) Appl. No.: **29/899,681**

(22) Filed: **Aug. 11, 2023**

(30) **Foreign Application Priority Data**

Jun. 7, 2023 (CN) 202330348343.7

(51) **LOC (15) Cl.** **09-06**

(52) **U.S. Cl.**

USPC **D8/356**; D8/367; D8/394

(58) **Field of Classification Search**

USPC D8/349, 354, 356, 367, 382, 383, 394;
D11/184

CPC F16L 3/12; F16L 3/123; F16L 3/123;
H02G 3/30; H02G 3/32

See application file for complete search history.

(57) **CLAIM**

The ornamental design for a wire clamp hook, as shown and described.

DESCRIPTION

FIG. 1 is a first perspective view of a wire clamp hook showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a third perspective view thereof, shown in a state of use.

The broken lines shown in the drawings depict environmental structure that forms no part of the claimed design.

1 Claim, 9 Drawing Sheets
